CLAIM

The ornamental design for combined multiple seating and table unit, as shown and described.

DESCRIPTION

FIG. 1 is a perspective view of a first embodiment of the combined multiple seating and table unit, according to the present design;

FIG. 2 is a top plan view thereof;

FIG. 3 is a front view thereof;

FIG. 4 is a right side view thereof;

FIG. 5 is a left side view thereof; and

FIG. 6 is a bottom view thereof;

FIG. 7 is a perspective view of a second embodiment of the design;

FIG. 8 is a top plan view thereof;

FIG. 9 is a front view thereof;

FIG. 10 is a right side view thereof;

FIG. 11 is a left side view thereof; and,

FIG. 12 is a bottom view thereof.

In the drawings, the broken lines depict portions of the combined multiple seating and table unit that form no part of the claimed design.

1 Claim, 8 Drawing Sheets
